[57] **ABSTRACT**

A strip of plastic, typically incorporated into the shape

of a plastic rule, is provided with a gradually increasing thickness along its longitudinal length. The thickness of the strip tapers between the minimum interstitial distance between a garment button flap and a button sewn to the garment to the maximum interstitial distance between the garment button flap and a button sewn to the garment. The tapered strip is notched at a plurality of typically evenly spaced intervals along its length at notches of sufficient width to permit buttons to be sewn. In operation, the side edge of the tapered strip is matched to the buttonhole thickness of the garment along the buttonhole flap. The nearest notch matching the desired buttonhole thickness and consequently the desired button shank length is selected. The notch is then positioned on the button flap of the garment underlying the buttonhole on the buttonhole flap of the garment. The button is sewn through the notch so that a length of thread between the button and the button flap garment of exact buttonhole thickness results. When the button is sufficiently secured by thread to the garment, the length of thread between the button and cloth of the garment is bound into semirigid shank by conventional sewing techniques.

FIG_2

BUTTON SHANK DEPTH GUIDE

This invention relates to devices for sewing buttons onto garments, and more particularly to a depth guide for obtaining the desired button shank depth in the interstitial space between the button shank and the garment.

SUMMARY OF THE PRIOR ART

The sewing of buttons requires that the length of thread in the interstitial distance between the button and the button flap of the garment match the thickness exactly of the buttonhole at the buttonhole flap of the garment. Surprisingly, this precise depth is often difficult to obtain.

The prior art has attempted many solutions. For example, discrete pieces of notched material have been used to sew buttons. Where a seamstress or tailor encounter many garments of differing buttonhole thicknesses, correspondent multiplicities of shank depth guides must be provided. The result is an unnecessarily large number of guides which are difficult to select and frequently lost and misplaced on the inevitably cluttered work area of a seamstress or tailor.

Likewise, specialized button shanks have been developed. These button shanks usually are sewn in between the button and the cloth of the garment button flap and have a length which matches the buttonhole depth of the garment.

The difficulty with these devices is that they have never been acceptable. Not only are many specialized fittings of different diameter and length required, but they additionally needlessly complicate the process of sewing on a button.

Finally, concentrically expanding step tapered button guides have, in the past, been used.

These step tapered button guides are severely restricted in their use. Not only is no provision for measurement of cloth buttonhole thickness provided, but additionally the depth of the shank varies as a function of the diameter of a circular button and not as a function of the depth of the garment buttonhole at the garment buttonhole flap. Where square or irregularly shaped buttons are used, such devices fail in their entirety.

SUMMARY OF THE INVENTION

A strip of plastic, typically incorporated into the shape of a plastic rule, is provided with a gradually increasing thickness along its longitudinal length. The thickness of the strip tapers between the minimum interstitial distance between a garment button flap and a button sewn to the garment to the maximum interstitial distance between the garment button flap and a button sewn to the garment. The tapered strip is notched at a plurality of typically evenly spaced intervals along its length at notches of sufficient width to permit buttons to be sewn. In operation, the side edge of the tapered strip is matched to the buttonhole thickness of the garment along the buttonhole flap. The nearest notch matching the desired buttonhole thickness and consequently the desired button shank length is selected. The notch is then positioned on the button flap of the garment underlying the buttonhole on the buttonhole flap of the garment. The button is sewn through the notch so that a length of thread between the button and the button flap garment of exact buttonhole thickness re-

sults. When the button is sufficiently secured by thread to the garment, the length of thread between the button and cloth of the garment is bound into a semirigid shank by conventional sewing techniques.

5 OTHER OBJECTS AND ADVANTAGES OF THIS INVENTION

An object of this invention is to disclose a one-piece rule which can serve as a button shank depth guide for 10 virtually all depths of desired button shank lengths.

An advantage of this invention is that no special button shanks or other non-conventional sewing attachments are required.

A further advantage of this invention is that the 15 closed button shank depth guide works with virtually all sizes and shapes of buttons. Shank depths are not a function of button size, but rather are varied only to the essential parameter of the thickness of the garment at the buttonhole cloth flap.

20 A further advantage of this invention is that the desired button shank depth is easily selected. By the simple expedient of sizing the tapering edge of the rule on which the shanks are placed to the observed garment thickness at the buttonhole, the necessary interstitial spacing for the button shank can be easily selected and provided.

Yet another advantage of the button shank depth guide of this invention is that the device can be incorporated into a simple sewing rule. By the expedient of 30 spacing notches for the placement of buttons at evenly spaced measuring intervals, the device can not only serve as a button shank depth guide but can double at the dimensions of the notches as an easy visual and even touch sensitive measurement of the desired distance between the garment flap edge and the position of the buttonhole.

Other objects, features and advantages of this invention will become more apparent after referring to the following specification and attached drawing in which:

40 FIG. 1 is a side elevation of the depth guide of this invention illustrating its taper from a narrow dimension at one end to a thicker dimension at the other end;

45 FIG. 2 is a plan view of the depth guide of this invention illustrating evenly spaced notches along its length and showing the invention incorporated into the side edge of a measuring rule;

50 FIG. 3 is a perspective view illustrating the selection of a particular notch for use to sew on a button by juxtaposing the rule to a buttonhole on a buttonhole flap of a garment; and,

55 FIG. 4 is an illustration of the apparatus of this invention being used to sew on a button, the button here being shown in concentric broken lines.

Referring to FIGS. 1 and 2, the dimension and construction of the button shank depth guide A can be easily understood. Preferably, the guide is incorporated in a rule not exceeding nine inches in length. As can be seen, the rule at edge 14 is provided with a conventional ruler scale 16 extending from one to nine inches in length.

60 The ruler tapers. It tapers from an initial thickness in the order of one sixty-fourth inch at end 18, to a thickness in the order of one-fourth inch at end 20.

65 A plurality of square notches are made in the side of the ruler. For uniformity these notches are all of the same dimension and spaced at one inch intervals along the length of the ruler. Notches 22 are spaced in the

ruler at the half inch graduations of scale 16. Preferably, the notches are centered at $\frac{1}{2}$, $1\frac{1}{2}$, $2\frac{1}{2}$, $3\frac{1}{2}$, $4\frac{1}{2}$, $5\frac{1}{2}$, $6\frac{1}{2}$, $7\frac{1}{2}$ and $8\frac{1}{2}$ inches.

It should be noted that with this regular spacing of the notches at 1 inch intervals, measurement with the rule is facilitated. Resort to the scale 16 to determine measurement is not required. Rather, the length between successive notches 22 can just as easily be used for measurement.

Referring to FIG. 3, the operation of this device may be easily understood. The device is first positioned at a buttonhole 27 adjacent a buttonhole flap B of a garment. The side edge of the tapered rule is juxtaposed to the folded over buttonhole. The depth of a preselected notch 22 is selected by visually matching the nearest notch thickness to the fabric thickness of buttonhole 27.

Referring to FIG. 4, button 30 is shown being sewn onto a button flap C of a garment. The button is placed so that the buttonholes 32 overlie the notch 22 in the edge of the rule. Sewing of the button 30 to the button flap of the garment C occurs by conventional methods. Similarly, binding of the shank occurs by conventional sewing techniques and no specialized tools or the like are required.

It should be apparent to those having skill in the art that the construction of this device can vary. It is not required that it be incorporated in a rule or that the notches be evenly spaced. Moreover, the taper of the

rule does not have to be linear. It can vary with non-linearity. Finally, the construction of the rule does not have to be of plastic. It can likewise be of wood, steel or any other suitable material.

I claim:

1. A button shank depth guide for guiding sewing of a button to cloth, said guide comprising an elongated tapered strip having two substantially planar opposite surfaces separated by a first thickness at one end of said strip and a second and greater thickness at the other end of said strip such that the distance between said opposite surfaces continuously increases from said first thickness to said second thickness, said strip having an elongate edge between said opposing surfaces, said edge being interrupted by a plurality of spaced apart notches extending between said opposite surfaces and through said strip, said depth guide adapted to be placed on said cloth with a selected notch positioned between said cloth and said button such that the shank of said button is in said notch, wherein the position of said button with respect to said cloth is determined by the thickness of said selected notch.

2. The invention of claim 1 and wherein said strip includes a linear measurement scale extending longitudinally along said strip adjacent to said notches.

3. The invention of claim 1 and wherein said notches are substantially rectangular in shape.
